LANTERN HANGER

Henry T. Honig, 5330 Royal Lane, Dallas, Tex.

Filed Feb. 4, 1964, Ser. No. 78,514

Term of patent 14 years

(Cl. D48—4)

FIGURE 1 is a perspective view of a lantern hanger, showing my new design;

FIGURE 2 is an enlarged side elevation of the hanger, showing the supporting chain in adjusted position for holding the lantern at an angle;

FIGURE 3 is a top plan view of the hanger of FIGURE 2;

FIGURE 4 is a bottom plan view of the hanger of FIGURE 2;

FIGURE 5 is a right end view of the hanger of FIGURE 2; and

FIGURE 6 is a left end view of the hanger of FIGURE 2.

The broken line showing of a lantern in FIGURES 1 and 2 and the broken line showing of a support in FIGURE 1 are for illustrative purposes only.

I claim:

The ornamental design for a lantern hanger, substantially as shown and described.
